Patented Dec. 6, 1921.

UNITED STATES PATENT OFFICE.

ALVA ARTHUR LINDLEY, OF SPOKANE, WASHINGTON.

OIL-BURNER.

1,399,218.

Specification of Letters Patent.

Patented Dec. 6, 1921.

Application filed June 28, 1920. Serial No. 392,245.

To all whom it may concern:

Be it known that I, ALVA ARTHUR LINDLEY, a citizen of the United States, and a resident of Spokane, in the county of Spokane and State of Washington, have invented certain new and useful Improvements in Oil-Burners, of which the following is a specification.

My invention relates to improvements in fuel oil burners in connection with hot water and steam furnaces or the like, whereby fuel oil may be effectively burned with efficiency. The purpose of the invention is to provide a self-cleaning fuel oil burner so constructed as to prevent or alleviate clogging, but which is provided with means for cleaning the same out with steam or hot water in case of necessity; to provide means whereby the regulation is automatic, according to the temperature of the heating plant; to provide means for maintaining the burner proper sufficiently heated at all times to facilitate gasification and burning of the oil; to obviate the necessity of supplying steam or hot water continuously to the oil for the purpose of burning the same, or forcing air thereto under pressure, and to permit the handling of all grades or mixtures and thicknesses of oil at different temperatures without changing the burner or nozzle.

A further object of the invention is to provide a fuel oil burner employing gravity instead of pressure operated feeding means, said burner being of simple and novel construction and provided with a hinged cover or flap door automatically operated in accordance with the heat generated to regulate the operation of the burner, while also permitting the parts to be easily cleaned and at the same time producing a device which can be very economically produced and maintained in good working order.

Other and further objects of my invention will become apparent to persons skilled in the art, from a consideration of the following description when taken in conjunction with the accompanying drawings, wherein:

Figure 1 is a plan view of my improved fuel oil burner.

Fig. 2 is a detail perspective view of the burner proper with the cover or cap thereof removed.

Fig. 3 is a detail view showing the device

connected for automatic operation or regulation in a steam heating plant, and

Fig. 4 is a similar view showing means for automatically regulating the position of the cover according to the temperature of the water in a hot water heating plant.

As illustrated in the drawings, in which like reference characters designate corresponding parts throughout the several views, the improved burner consists of a burner body or nozzle 5 of substantially relatively flat rectangular formation having a sloping portion 6 at the front portion of the top thereof, preferably formed with ears or the like 7 at either side of a central recess 8 for attachment of a flap door or hinged cover 9 which is normally held closed through the medium of springs or the like 10 engaged at the hinged connections 11 thereof. Extending longitudinally of the body is an orifice or passage 12 which terminates at the recess 8 in a flaring mouth portion or nozzle 13 having an inclined bottom wall and diverging tapered side walls, as clearly shown in Fig. 2 of the drawings.

The passage 12 extends medially of the upper portion of the burner body, and extending transversely across the lower portion of the body beneath the passage 12 is a passage 14 from which extend at right angles thereto and parallel to each other, a pair of pilot burner orifices 15 which communicate with the front edge or end of the burner body. Extending from a suitable source of fuel oil supply is a tube or pipe line 16, said fuel line being connected with a reservoir or tank containing oil which may be supplied with air under pressure if desired. This pipe is connected to the opening 12 and has interposed therein, a valve 17. Between the valve 17 and the burner is interposed a valve 18, while arranged between the valves 17 and 18 and nearer the former, is a connection or pipe 19 leading from a source of steam or hot water supply which may be connected to a steam or hot water heating system in connection with which the device is used. The pipe 19 is provided with a valve 20 by means of which the supply of hot water or steam is controlled and between the pipe 19 and the valve 18 extends a pipe or tube 21 for the pilot burners or lights, the same being preferably of curved or arcuate formation extending

into the opening or passage 14 in the burner proper. This pipe is provided with a valve 22 by means of which the supply of oil to the pilot burner may be effectively regulated.

Thus, it will be seen in the operation of the burner, the valve 17 is opened while the valves 18 and 20 are closed, and with the valve 22 slightly open, so as to initially supply the oil to the pilot burner to be lighted. The burner body is then heated to sufficient degree with the valve 18 slightly opened, to facilitate burning of the oil at the orifice 13, after which the valve 22 may be slightly cut off. Of course, the flap door or cover 19 is opened manually or automatically to permit the oil exuding from the burner to be ignited and the heat from the pilot burner will facilitate gasification thereof, in order to produce an intense heat. The cover 9 is provided with suitable means designated at 23 by which connection is made to a suitable lever 24 automatically operated by a diaphragm regulator 25 or a thermostatic regulator 26 as preferred in practice, to open or close the gate or cover in the burner as the steam increases or decreases in pressure or as the hot water of the heating system increases or decreases in temperature, thereby making an automatic self-cleaning burner, although the latter can be operated by hand if the regulator becomes inoperative for any reason.

Of course, it is to be understood that the pilot light burns all the time, and by providing two of the burner passages or nozzles, it is insured that one at least shall be open so that when the main burner is opened by the regulator, the same will be instantly lighted because of the temperature to which the same has been raised by the heat thus applied. Furthermore, in the event that the burner becomes clogged, the valves 17 and 22 are closed, while opening the valves 18 and 20, thus allowing the pipe to be blown out or cleared, as well as the burner, by the hot water or steam forced therethrough under pressure. Should the pilot burners become clogged, the valves 17 and 18 are closed and the valves 20 and 22 opened, thus permitting the steam or water to be forced through the pipe 21 and through the nozzles 15 to effectively clean out the pilot burner nozzles. When the device is in operation, the valve 17 is opened to the fuel tank and also the valve 18, while the valve 20 may be slightly opened if desired. The valve 22 is also set at the proper degree of opening to allow the pilot burner to continuously operate for keeping the burner body warm and for igniting the same if desired, regulation being effected as heretofore specified. I do not wish to limit myself to any particular application of the device but I claim more especially, the arrangement of parts consti-

tuting the burner, including the burner body and hinged cover or gate for the burner orifice, which is so shaped as to form an elongated outlet end between the cover and the sloping bottom wall of the orifice, thus eliminating in connection with the automatic regulation, the liability of clogging experienced by round orifice burners. Furthermore, the device can be readily and effectively cleaned out and no air pressure is used to force the fuel oil through the burner, gravity being employed for this purpose, owing to the pre-heating of the oil by the pilot burners. While the tank or reservoir may be supplied with air under pressure, this is not essential to the use of the present device as in connection with round orifice burners owing to the difficulty experienced in obtaining the proper temperature and which in connection with the round orifice burner, results in a moisture deposit in the fuel oil which finds its way into the jet, thus causing the clogging of the burner. While I do not desire to be limited to the use of any particular material, the parts are preferably constructed of brass or copper, or may be made of iron with the connections made oil-tight. The device will handle all grades or mixtures and thicknesses of oil of different temperatures without changing the burner or nozzle and without clogging.

In view of the foregoing, it is thought that the operation of the device will be readily understood and in view of the simplicity and practical value that it will commend itself to those skilled in the art.

Having thus described my invention, what I claim is:

1. A fuel oil burner comprising a relatively rectangular body having a sloping forward portion at the top thereof and a passage provided with a burner orifice having diverging side walls and an inclined bottom wall forming an elongated passage, and a hinged cover for said sloping portion over said passage and adapted to be regulated according to the temperature or pressure of the heating plant.

2. A fuel oil burner comprising a burner nozzle including a relatively flat body having a passage extending centrally therethrough and terminating in a recess having an inclined bottom wall and diverging side walls, a hinged gate co-operating with said sloping portions to form an elongated slot at the orifice of said recess, means for connection of said gate with a regulator to automatically control the position thereof according to the temperature or pressure of the heating plant to which the device is applied, and means for supplying fuel to said passage.

3. A fuel oil burner comprising a burner nozzle including a relatively flat body having a passage extending centrally there-

- through and terminating in a recess having an inclined bottom wall and diverging side walls, a hinged gate coöperating with said sloping portions to form an elongated slot
- 5 at the orifice of said recess, means for connection of said gate with a regulator to automatically control the position thereof according to the temperature or pressure of the heating plant to which the device is
- 10 applied, said body having a transverse passage provided with pilot burner nozzles extending from the same to the forward edge thereof for initially heating the oil supplied to the burner nozzle passage, a valve connection with the first named passage, a source of oil supply, and a valve connection between said first named connection and the pilot burner passage for independently or simultaneously operating the same.
- 15 4. A burner of the class described comprising a nozzle body having a passage longitudinally thereof and terminating in a flaring orifice, a movable plate hingedly co-operating with said orifice and adapted to be automatically regulated in its relation with respect thereto, a transverse passage leading through one side of the body of the nozzle and having right angularly extending orifices leading through the front edge thereof
- adjacent to, beneath and at each side of said first named orifice, a valved pipe, a source of fuel supply having connection with said first named passage, a second valve interposed in said pipe connection, a valved branch pipe leading to said first named pipe connection between said valve connections thereof and having connection with a source of hot water or steam supply, and a valve connection between the last named supply connection and the second named valve and curved laterally for communication with the pilot burner passage for controlling the latter.
5. The combination with a heating plant with hot water or steam supply and a burner having connection with an automatic regulator controlled by said supply, said burner comprising a body having a discharge orifice of elongated formation and a hinged cover normally closed and connected with said regulator; of a pilot burner passage extending transversely of the body and having nozzles extending at right angles therefrom to the forward edge of the body, and means whereby oil or hot water and steam may be independently supplied to said burners.

ALVA ARTHUR LINDLEY.
